**1-(2-METHYL-4-AMINO-5-PYRIMIDYL)METHYL-
LOWER ALKYL PYRIDINIUM QUATERNARY
SALTS FOR TREATING COCCIDIOSIS**

EDWARD F. ROGERS, MIDDLETOWN, AND LEWIS H. SARETT,
PRINCETON, N.J., ASSIGNEES TO MERCK & CO., INC., Rah-
way, N.J., A CORPORATION OF NEW JERSEY
NO DRAWING. ORIGINAL APPLICATION JULY 28, 1959, SER.
NO. 329,978. DIVIDED AND THIS APPLICATION JUNE 24,
1960, SER. NO. 38,451.

11 Claims. (Cl. 167—53.1)

This invention relates generally to new chemical compounds. More specifically, it is concerned with chemical compounds which are useful in the prevention and the cure of coccidiosis. Still more particularly, it is concerned with a group of new pyridinium quaternary salts which are effective in controlling coccidiosis when fed in relatively small amounts to poultry. Still more specifically, it relates to 1-(2-methyl-4-amino-5-pyrimidylmethyl)-loweralkyl pyridinium quaternary salts and with methods of making such substances. It is further concerned with novel compositions containing such substances.

This application is a division of our copending application Serial No. 829,978, filed July 28, 1959, now abandoned, which in turn is a continuation-in-part of our application Serial No. 805,688, filed April 13, 1959, now abandoned.

Coccidiosis is a common and widespread poultry disease caused by several species of protozoan parasites of the genus *Eimeria*, such as *E. tenella*, *E. necatrix*, *E. acervulina*, *E. maxima*, *E. hagani* and *E. brunetti*. *E. tenella* is the causative agent of a severe and often fatal infection of the ceca of chickens which is manifested by extensive hemorrhage, accumulation of blood in the ceca, and the passage of blood in the droppings. *E. necatrix* as well as certain other species attack the small intestine of the chick causing what is known as intestinal coccidiosis. Related species of coccidia such as *E. melagagridis* and *E. adenoides* are causative organisms of coccidiosis in turkeys. When left untreated, the severe forms of coccidiosis lead to poor weight gain, reduced feed efficiency and high mortality in fowl. The elimination or control of coccidiosis is, therefore, of paramount importance in the poultry raising industry.

It has now been found that certain pyridinium quaternary compounds are highly active against the protozoa responsible for coccidiosis. One object of the invention is to provide such compounds. Another object is to provide a synthesis of such substances. A further object is the provision of animal feeds and feed supplements and of water soluble compositions containing these pyridinium quaternary salts. Other objects will be apparent from the following discussion of our invention.

According to this invention it has been found that 1-(2-methyl-4-amino-5-pyrimidylmethyl)-loweralkyl pyridinium quaternary salts, and particularly those compounds wherein the pyridine ring is substituted with from one to three lower alkyl groups, are very effective in preventing and treating coccidiosis. The compounds of the invention are pyridinium quaternary salts of the formula

2

wherein R is a lower alkyl radical, n has a value of 1, 2 or 3, and X is an anion; b and c are positive numbers having values such that the positive charge of b moles of cation is neutralized by c moles of anion X. Thus when X is a monovalent anion such as a halide, b is 1 and c is 2. When more than one lower alkyl group is present in the pyridine ring, i.e. when n is 2 or 3, such lower alkyl groups may be the same or different. As described more fully below, these anticoccidial compounds are prepared by reaction of a 2-methyl-4-amino-5-substituted methyl pyrimidine with an appropriately alkylated pyridine. As will be apparent from the above structural formula, the anticoccidial compounds described herein may be considered as substituted pyridines. The pyridine ring is substituted at the 1-position by a 2-methyl-4-amino-5-pyrimidylmethyl radical; in the preferred compounds, it is further substituted with one or more lower alkyl groups, such as methyl, ethyl, propyl, isopropyl, butyl and amyl groups, such substituents being in at least the 2, 3 and/or 4 positions of the ring. The lower alkyl groups present in the pyridine ring of these compounds need not, of course, be the same in any particular compound.

The preferred compounds of the invention are 1-(2-methyl-4-amino-5-pyrimidylmethyl)-2-loweralkylated pyridinium salts and 1-(2-loweralkyl-4-amino-5-pyrimidylmethyl)-4-loweralkylated pyridinium salts, i.e. compounds having a lower alkyl radical at least at the 2 or 4 position in the pyridine ring. Included among these are 1-(2-methyl-4-amino-5-pyrimidylmethyl)-2-methyl pyridinium chloride hydrochloride, 1-(2-methyl-4-amino-5-pyrimidylmethyl)-2-methyl-5-ethyl pyridinium chloride hydrochloride, 1-(2-methyl-4-amino-5-pyrimidylmethyl)-4-ethyl pyridinium bromide hydrobromide, 1-(2-methyl-4-amino-5-pyrimidylmethyl)-4-methyl pyridinium acetate and 1-(2-methyl-4-amino-5-pyrimidylmethyl)-2-methyl pyridinium bromide hydrobromide.

The quaternary anion may be an inorganic anion such as chloride, bromide, iodide, nitrate, sulfate, phosphate and the like, or the anion of an organic acid such as citric, tartaric, acetic, picric, stearic, succinic, benzoic, phthalic, phenoxyacetic, embonic, abietic, 2-naphthalene sulfonic or ethylenediamine tetracetic acids. It may also be the anion of a polymer such as a polyphosphate or polystyrenesulfonate ion. The nature of the anion is not critical and any anion may be employed as long as it is not unduly toxic for the poultry. It will be realized that an acid addition salt of the primary amino group present in these compounds will also be formed concurrently with the quaternary salt.

55 The compounds described herein are synthesized by reacting together an appropriately substituted pyrimidine and an alkylated pyridine. According to one process, a 2-methyl-4-amino-5-halomethyl pyrimidine dihydrohalide, in which the halogen is bromine or chlorine, is reacted 60 directly with the alkylated pyridine. An excess of the liquid alkylated pyridine or alternatively organic solvents inert under the reaction conditions such as lower alkanols, acetonitrile or an N,N-dilower alkyl alkanoamide may be employed as the reaction medium. The temperature 65 is not critical and it is preferred to carry out the process at about room temperature. After a short time the quaternary salt crystallizes and is recovered by known

technique such as filtration or centrifugation. This process may be represented as follows:

where R is a lower alkyl radical, n is 1-3 inclusive and X is chlorine or bromine.

Although the 5-halomethyl pyrimidines are generally most conveniently employed for reaction with the alkyl pyridine, the quaternization may also be brought about with an ester of 2-methyl-4-amino-5-hydromethyl pyrimidine. Suitable esters are the methylsulfinate, p-toluenesulfonate and nitrate esters. The quaternization may be conducted so that the particular salt desired for treating coccidiosis is obtained directly. Alternatively, the quaternary salt recovered from the synthetic reaction medium may be conveniently metathesized to another salt by techniques known in the art.

In using the compounds of the invention in the treatment and prevention of coccidiosis, they are conveniently fed to poultry as a component of the feed of the animals although they may also be given dissolved or suspended in the drinking water. According to one aspect of the invention, novel compositions are provided in which compounds described above are present as an active anticoccidial ingredient. Such compositions comprise the quaternary salts intimately dispersed in or admixed with an inert carrier or diluent. By an inert carrier is meant one that is nonreactive with respect to the quaternary salt and that may be administered with safety to the animals. The carrier or diluent is preferably one that is or may be an ingredient of the animal feed.

The compositions which are a preferred feature of the invention are the so-called feed supplements in which the active ingredient is present in relatively large amounts and which are suitable for addition to the poultry feed either directly or after an intermediate dilution or blending step. Examples of carriers or diluents suitable for such compositions are solid orally ingestable carriers such as distillers' dried grains, corn meal, citrus meal, fermentation residues, ground oyster shells, Attapulgus clay, wheat shorts, molasses solubles, corn cob meal, edible vegetable substances, toasted dehulled soya flour, soybean mill feed, antibiotic mycelia, soya grits, crushed limestone and the like. The quaternary salts are intimately dispersed or admixed throughout the solid inert carrier by methods such as grinding, stirring, milling or tumbling. By selecting proper diluents and by altering the ratio of carrier to active ingredient, compositions of any desired concentration may be prepared. Formulations containing from about 1% to about 40% by weight, and preferably from about 2-25% by weight of active ingredient are particularly suitable for addition to poultry feeds, and compositions containing from about 5-15% by weight of coccidiostat are very satisfactory. The active compound is normally dispersed or mixed uniformly in the diluent but in some instances may be sorbed on the carrier. The optimal concentration of coccidiostat in these feed supplements will depend to some extent on the particular compound employed. Since it is convenient for the feed manufacturer to use about one pound of feed supplement for each ton of finished feed, the preferred concentration of any one of our coccidiostats in a feed supplement is partly a function of the level of active ingredient desired in the finished feed.

Examples of typical feed supplements containing a pyridinium quaternary salt dispersed in a solid inert carrier are:

A. 1-(2-methyl - 4 - amino - 5 - pyrimidylmethyl)-4-
methyl pyridinium chloride hydrochloride--- 6.0
Wheat standard middlings----- 94.0

B. 1-(2-methyl-4-amino-5-pyrimidylmethyl)-2-
methyl pyridinium bromide hydrobromide--- 10.0
Lbs.

10 Corn distillers' dried grains----- 90.0
C. 1-(2-methyl - 4 - amino - 5 - pyrimidylmethyl)-2-
methyl-5-ethyl pyridinium chloride hydrochloride----- 15.0
Wheat standard middlings----- 85.0
15 D. 1-(2-methyl - 4 - amino - 5 - pyrimidylmethyl)-2-
methyl pyridinium chloride hydrochloride--- 20.0
Corn germ meal----- 30.0
Corn distillers' grains----- 50.0
E. 1-(2-methyl - 4 - amino - 5 - pyrimidylmethyl)-4-
ethyl pyridinium bromide hydrobromide--- 12.0
Wheat standard middlings----- 88.0

These and similar feed supplements are prepared by uniformly mixing the pyridinium quaternary salt with the carrier or carriers.

The feed supplements of the type illustrated hereinabove are usually further diluted with materials such as corn meal or soybean meal before being incorporated in the animal feed. In this intermediate processing step the level of coccidiostat in the carrier is brought down to from about 0.1% to about 1.0% by weight. This dilution serves to facilitate uniform distribution of the substance in the finished feed. The finished feed is one that contains a source of fat, protein, carbohydrate, minerals, vitamins and other nutritional factors.

The amount of pyridinium quaternary salt required for control of coccidiosis in poultry will, of course, vary somewhat with the specific compound or compounds employed. The compounds of Formula I above are effective in preventing the disease when administered at levels of less than about 0.05% by weight of the feed. With the preferred compounds of the invention, i.e. the 1-(2-methyl-4-amino-5-pyrimidylmethyl)-2-lower alkyl pyridinium and 1-(2-methyl-4-amino-5-pyrimidylmethyl)-4-lower alkyl pyridinium salts, good prophylactic results were obtained when from about 0.01% to about 0.05% by weight of the total feed consumed is administered; for most satisfactory results it is preferred that the poultry feed contain between about 0.005% and 0.025% by weight of pyridinium salt. When the pyridinium salts are to be employed as therapeutic agents, the higher levels are used for relatively short periods of time. Thus, concentrations of about 0.02% to 0.05% by weight of the feed may be advantageously administered in treating an established outbreak of coccidiosis. It is desirable to employ the lowest levels that afford fully adequate control of coccidiosis in order to eliminate as far as possible any risk of side effects that might appear on prolonged feeding of the compounds.

Many of these pyridinium quaternary salts are desirably or advantageously administered to poultry by way of the drinking water of the birds. This method of treatment is often employed in the therapeutic use of our compounds since poultry with coccidiosis are apt to consume less solid feed than normal birds. The water-soluble quaternary salts may be added directly to the drinking water. Alternatively, water-soluble powders may be prepared, in which the coccidiostat is intimately admixed with a suitable carrier, such as dextrose or sucrose, and these powders added to the drinking water of poultry as necessary. Such water-soluble powders may contain any desired concentration of coccidiostat, and preparations containing from 1-25% by weight of active ingredient are suitable.

EXAMPLE 1

To 25 ml. of 2-methylpyridine (α -picoline) was added 75 a solution of 20 grams of 2-methyl-4-amino-5-pyrimidyl-

methyl bromide dihydrobromide in 100 ml. of methanol. A clear solution formed which became slightly warm. 100 ml. of absolute ethanol was added. In a short time crystals of 1-(2-methyl-4-amino-5-pyrimidylmethyl)-2-

6
EXAMPLE 4

The pyridinium quaternary salts set forth in Table I below were synthesized utilizing processes described in preceding examples.

Table I

Cpd. No.	R ¹	R ²	R ³	R ⁴	R ⁵	R ⁶	X	Quaternary Prepared By Method of Ex. No.	Melting Point °C. (dec.)	Percent In Feed ^a

^a Anticoccidial activity of the compounds described in the above table was determined by the following test:

Straight run White Leghorn chicks, in groups of three each, were weighed and placed in cages with wire floors. They were fed ad libitum a standard laboratory basal ration in which graded levels of the pyridinium quaternary salt were intimately dispersed or blended. Normal and infected control birds were fed basal ration containing no quaternary salt. On the second day of test, the chicks were each orally inoculated with 50,000 sporulated oocysts of *Emeria tenella*. Papers under the cages were examined on the sixth, seventh and eighth days of assay for the presence or absence of bloody droppings. A score of 0 was given if no bloody spots were observed; scores of 1, 2 or 4 were assigned for 1-3, 4-6 and >6 bloody spots, respectively. On the eighth day of assay, the surviving birds were weighed, sacrificed and examined grossly for cecal coccidiosis lesions. Normal ceca were scored 0, and ceca with detectable, moderate or maximal lesions were scored 1, 2 and 4, respectively. When a bird died and cecal coccidiosis lesions were present, a score of 5 was recorded. If the total of the two scores was 0-5, the compound under test was rated "active" if the total score was 6 or more, the compound was rated "inactive" at the concentration tested.

methylpyridinium bromide hydrobromide began to appear. The mixture was allowed to stand in the cold for about 15 hours. The crystalline material was then collected by filtration, washed with two 20 ml. portions of cold absolute ethanol and dried. The small white crystals of 1-(2-methyl-4-amino-5-pyrimidylmethyl)-2-methylpyridinium bromide hydrobromide thus obtained melt at 233-234° C. (dec.).

EXAMPLE 2

One gram of 1-(2-methyl-4-amino-5-pyrimidylmethyl)-2-methyl pyridinium bromide hydrobromide was dissolved in 4 ml. of concentrated hydrochloric acid. This solution was carefully diluted with 60 ml. of acetone whereupon 1-(2-methyl-4-amino-5-pyrimidylmethyl) - 2 - methyl pyridinium chloride hydrochloride crystallized. This salt was dissolved in 2 ml. of concentrated hydrochloric acid and the solution slowly diluted with 40 ml. of acetone. The salt crystallized and on drying melted to 256-7° C. (dec.).

EXAMPLE 3

To 7.5 parts of 2-methyl-4-amino-5-pyrimidylmethyl bromide dihydrobromide in 50 parts of acetonitrile was added 9 parts of 2,3-dimethyl pyridine. The mixture warmed and became clear. Shortly, 1-(2-methyl-4-amino-5 - pyrimidylmethyl) - 2,3 - dimethyl pyridinium bromide hydrobromide began to crystallize. The crystals were collected after standing overnight, and recrystallized from 50 parts of methanol and 150 parts of acetone, melting point 208° C. (dec.).

The compounds described in Table I, when tested by this method, were found to be active (total score of 0-5) at the dose level indicated.

EXAMPLE 5

The coccidiostatic activity of two of the pyridinium compounds of the invention was determined by the following method:

Groups of ten two-week old White Leghorn chicks 55 were fed a mash diet containing various amounts of the compounds. The compounds were uniformly dispersed in the feed. After having been on this ration for 24 hours, each chick was inoculated with 50,000 sporulated oocysts of *E. tenella*.

Other groups of ten chicks each were fed a similar 60 mash diet which contained no coccidiostat. These were also infected after 24 hours and served as positive or infected controls. As positive controls, two to four groups of ten chicks each were employed. Still other 65 groups of ten chicks each were fed the mash free of coccidiostat and were not infected with coccidiosis. These served as normal controls.

The diets were administered to the chicks for eight 70 days following the date of infection. At the end of this time, the infected birds still living were sacrificed. The oocyst count was determined by a microscopic examination of the cecal homogenates.

The results employing the indicated amounts of quaternary salt, and expressed as mean values, are set forth 75 in Table II.

Any departure from the above description which conforms to the present invention is intended to be included within the scope of the claims.

What is claimed is:

1. A poultry feed supplement composition that comprises an edible carrier having dispersed therein from about 1% to about 40% by weight of a quaternary compound of the formula

wherein R is methyl, and X is a non-toxic anion.

2. A composition useful against coccidiosis that comprises an edible carrier having intimately dispersed therein from about 1% to about 40% by weight of a 1-(2-methyl-4-amino-5-pyrimidylmethyl)-2-methyl pyridinium quaternary salt, wherein the anion of the salt is a non-toxic anion.

3. A composition useful against coccidiosis that comprises an inert edible carrier having intimately dispersed therein from about 1% to about 40% by weight of 1-(2-methyl-4-amino-5-pyrimidylmethyl)-2-methyl-5-ethyl pyridinium chloride hydrochloride.

4. A composition useful against coccidiosis that comprises an inert edible carrier having intimately dispersed therein from about 1% to about 40% by weight of 1-(2-methyl-4-amino-5-pyrimidylmethyl)-2-methyl-5-ethyl pyridinium halide hydrohalide.

5. An animal feedstuff having dispersed therein from about 0.005% to about 0.05% by weight of 1-(2-methyl-

4-amino-5-pyrimidylmethyl)-2-methyl pyridinium halide hydrohalide.

6. An animal feedstuff having dispersed therein from about 0.005% to about 0.05% by weight of 1-(2-methyl-4-amino-5-pyrimidylmethyl)-2-methyl-5-ethyl pyridinium chloride hydrochloride.

7. A composition comprising an inert edible carrier having dispersed therein a member of the class consisting of 1-(2-methyl-4-amino-5-pyrimidylmethyl)-2-methyl pyridinium quaternary salt and 1-(2-methyl-4-amino-5-pyrimidylmethyl)-2-methyl pyridinium quaternary salt having a lower alkyl group at one of the 3-, 4- and 5-positions of the pyridine ring, wherein the anion of the quaternary salt is a non-toxic anion; and non-toxic acid addition salts thereof.

8. A poultry feed supplement composition that comprises a poultry feed additive having dispersed therein from about 1% to about 40% by weight of a member of the class consisting of 1-(2-methyl-4-amino-5-pyrimidylmethyl)-2-methyl pyridinium quaternary salt and 1-(2-methyl-4-amino-5-pyrimidylmethyl)-2-methyl pyridinium quaternary salt having a lower alkyl group at one of the 3-, 4- and 5-positions of the pyridine ring, wherein the anion of the quaternary salt is a non-toxic anion; and non-toxic acid addition salts thereof.

9. A poultry feedstuff containing as an active anticoccidial ingredient a member of the class consisting of 1-(2-methyl-4-amino-5-pyrimidylmethyl)-2-methyl pyridinium quaternary salt and 1-(2-methyl-4-amino-5-pyrimidylmethyl)-2-methyl pyridinium quaternary salt having a lower alkyl group at one of the 3-, 4- and 5-positions of the pyridine ring, wherein the anion of the quaternary salt is a non-toxic anion; and non-toxic acid addition salts thereof.

10. The composition of claim 9 wherein the feedstuff contains from about 0.005% to about 0.05% by weight of quaternary salt.

11. A water-soluble powder comprising an edible water-soluble carrier having dispersed therein from about 1% to about 25% by weight of a member of the class consisting of 1-(2-methyl-4-amino-5-pyrimidylmethyl)-2-methyl pyridinium quaternary salt and 1-(2-methyl-4-amino-5-pyrimidylmethyl)-2-methyl pyridinium quaternary salt having a lower alkyl group at one of the 3-, 4- and 5-positions of the pyridine ring, wherein the anion of the quaternary salt is a non-toxic anion; and non-toxic acid addition salts thereof.
